(57) **CLAIM**

The ornamental design for a galley including a retractable bar for a vehicle, as shown and described.

DESCRIPTION

FIG. 1 is a perspective view of a galley including a retractable bar for a vehicle in a deployed position showing our new design;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof;

FIG. 8 is a perspective view of the galley including the retractable bar stowed in an alternate position;

FIG. 9 is a front view thereof;

FIG. 10 is a back view thereof;

FIG. 11 is a first side view thereof;

FIG. 12 is a second side view thereof;

FIG. 13 is a top view thereof; and,

FIG. 14 is a bottom view thereof.

The broken lines illustrate portions of the galley including a retractable bar for a vehicle, that form no part of the claimed design. The broken lines illustrating a set of drinking glasses show environmental structure that forms no part of the claimed design.

1 Claim, 8 Drawing Sheets
